UNITED STATES PATENT OFFICE

LUTHER JOHN VAN DELINDER AND AMASA WILLIAMS NASH, OF GARFIELD,
IOWA.

SPRING-BED.

SPECIFICATION forming part of Letters Patent No. 333,363, dated December 29, 1885.

Application filed March 29, 1884. Serial No. 126,021. (No model.)

To all whom it may concern:

Be it known that we, LUTHER JOHN VAN DELINDER and AMASA WILLIAMS NASH, both of Garfield, in the county of Jones and State 5 of Iowa, have invented a new and Improved Spring-Bed, of which the following is a full, clear, and exact description.

The object of this invention is to improve the construction of spring-beds; and it consists in the construction and combination of parts, as will be hereinafter fully described and claimed.

Reference is to be had to the accompanying drawings, forming part of this specification, 15 in which similar letters of reference indicate corresponding parts in all the figures.

Figure 1 is a plan view of our improved bed, parts being broken away. Fig. 2 is a side view of the same, parts being broken 20 away and in section. Fig. 3 is a view of two springs connected or formed of a continuous piece of wire.

A A indicate three longitudinal bars, upon which are secured transverse slats B for about two-thirds the length of the bars A, which slats will vary in number according to the size of the bed. Three (more or less) transverse slats, B', are secured together by short bars A', to form a head-rest frame C, which 25 bars A' are above and rest upon the bars A when the head-rest frame is lowered. A transverse rod, D, passes through the inner ends of the bars A', and has its ends held to the outer bars A by long staples E, as shown, 30 but slotted plates attached to the bars A will be preferred in practice, by which arrangement the inner end of the head - rest frame C can have a longitudinal movement upon the bars A, the ends of the rod D engaging with the staples or guides E, to hold 35 the head-rest frame from tilting. Braces F are pivoted to the bars A' about midway of the same, and extend to and are pivoted to the bars A near their ends. Across the bars 40 A, outside of the braces F, a transverse bar, B', is secured. Upon the middle bar A, beneath the head-rest frame, a ratchet, G, is secured, having its teeth inclined toward the outer end of said bar A, and a pawl, H, adapted 45 to engage the teeth of the ratchet G, extends to and is pivoted by its forked arms g to the

lower end of the middle bar A' of the head-rest frame C by the transverse rod D.

Upon the transverse bars B B' are secured in any suitable manner the springs I of the bed, which springs are preferably made in the form of an inverted pyramid—that is, the wire forming the said springs is bent rectangularly and downwardly, instead of being curved spirally and downwardly, as in the common bed-spring—and these springs may be made singly or in pairs of one piece of wire. By this form of spring the sides and ends of the bed can be made square with the upper surface of the same. The upper wires 60 of the springs are in closer proximity and are better adapted to sustain evenly any weight placed upon them.

Light bars J J' and K K' are secured to and longitudinally and transversely of the bed 70 and head-rest frames. Strips L, of webbing or other material, are placed upon the springs I longitudinally and transversely of the bed and head-rest frames, which strips L extend and are secured to the strips J J' and K K'. The strips L interlace with each other, and by this arrangement there are two thicknesses of material above each spring. The springs are secured to the webbing strips of canvas or other fabric and at four points by cords l l' 75 crossing each other and the springs, as shown in dotted lines in Fig. 1. A cord, M, is attached to the pawl H near its free end, which cord passes through a guide-hole in the middle bar A', thence to the side of the head-rest 80 frame.

When the outer end of the head-rest frame is raised, the pawl H engages by its own gravity with the rack G. The rod D slides backward in the staples or plates E as the said frame 85 swings upward and backward upon the braces F, and the head-rest always assumes a level position transversely, as there is but one ratchet at the center of the frame, and the inward thrust of the braces F with the tension 90 on the webbing L insures the hold of the pawl H upon the ratchet G.

To lower the head-rest it is only needful to pull upon the cord M, which disengages the pawl from the ratchet, leaving the head-rest 95 free to be lowered.

We are aware that it is not broadly new

to support a head-rest frame by means of pivoted side braces, to hold a head-rest frame in a raised position by pawls and ratchets, nor to provide trip devices for such pawls; but 5 our construction and arrangement of a head-rest frame, as herein described, differs materially from similar devices in placing the longitudinal bars of the head-rest frame in line with, and to have bearing on, the corresponding bars of the main frame, by which disposition of the bars less strain is thrown on the side braces and the ratchets and pawl; in passing a rod, D, through the lower ends of all the longitudinal bars of the head-rest frame, 5 which rod, with the side guides, E, pivots and keeps the lower end of the head-rest frame in place and also prevents tilting or side movement of the said frame, and in using a single centrally-arranged ratchet and pawl, which o arrangement is rendered possible by the other improved arrangements of parts. The pawl is so pivoted on rod D that it is securely attached to the head-rest frame. The head-rest can be easily manipulated by a single attendant

and will automatically take a level position. 25

The bed is simple and strong in construction, neat in appearance, and has few parts to get out of order.

Having thus described our invention, what we claim as new, and desire to secure by Letters Patent, is—

In a spring-bed, the combination, with the main frame A B, provided with guides E, the head-rest frame A' B', having its longitudinal bars in line with and their lower ends resting 35 on the longitudinal bars of the main frame, the rod D, connecting the lower ends of all the said bars of the head-rest frame, and having its ends extending into the guides E, and with the braces F, of the centrally-arranged rack G 40 and pawl H, said pawl H being pivoted on the rod D, and of the trip-cord M, substantially as shown and described.

LUTHER JOHN VAN DELINDER.
AMASA WILLIAMS NASH.
